UNITED STATES PATENT OFFICE.

CHARLES THOMAS JEARLES, OF BINGHAMTON, NEW YORK.

TILL-LOCK.

SPECIFICATION forming part of Letters Patent No. 448,962, dated March 24, 1891.

Application filed June 11, 1890. Serial No. 355,080. (Model.)

To all whom it may concern:

Be it known that I, CHARLES THOMAS JEARLES, residing in Binghamton, in the county of Broome and State of New York, 5 have invented a new and Improved Till Combination Lock and Alarm, of which the following is a full, clear, and exact description.

The object of the invention is to provide a new and improved combination lock and 10 alarm specially adapted for money-drawers, which is very simple and durable in construction, locking the drawers securely and at the same time permitting a quick opening of the same by the operator, who knows the combination, and also giving an alarm.

The invention consists of certain parts and details and combinations of the same, as will be fully described hereinafter, and then pointed out in the claims.

20 Reference is to be had to the accompanying drawings, forming a part of this specification, in which similar letters of reference indicate corresponding parts in all the figures.

Figure 1 is a sectional side elevation of the improvement. Fig. 2 is a plan view of the same. Fig. 3 is a sectional side elevation of part of the same on the line xx of Fig. 4, looking in the direction of the arrow x' . Fig. 4 is a plan view of the improvement with the 25 top plates of the casing removed. Fig. 5 is an enlarged sectional side elevation of the improvement on the line yy of Fig. 4. Fig. 6 is a like view of the same on the line zz of Fig. 4. Fig. 7 is an enlarged sectional side elevation 30 of part of the same on the line xx of Fig. 4, looking in the direction of the arrow x' . Fig. 8 is a perspective view of the locking-bar, and Figs. 9 and 10 show two of the tumblers.

40 The till or money-drawer A is held to slide in suitable guideways on the under side of the fixed table B, and in the rear end of the said till A is held a casing C, open at the bottom and closed at the top, being provided in 45 the latter with a transverse slot D, in which operates the cross-piece E' of the U-shaped locking-bar E, pivoted at E^2 to the sides of the casing C. The casing C is provided with a number of longitudinal partitions C', between which are held, in sets of 50 two, the tumblers F, F', F⁶, and F⁷, held to slide longitudinally and resting on trans-

verse pins G, secured to the sides of the casing C, and the tumblers F' are notched in the lower edges to hold them in position. 55 There are four of the tumblers F' and two each of the tumblers F, F⁶, and F⁷, which are of the same length but shorter than the tumblers F', and the corresponding ends of all the tumblers are marked a , b , c , d , and e . The 60 tumblers F, F⁶, and F⁷ are provided centrally their lower edge with a narrow slot F⁸, and the tumblers F' centrally their lower edge with a wide slot F⁴. The tumblers F are rounded at one upper corner F⁵ and provided 65 with a slot F², somewhat removed from the center toward the other end. The tumblers F' are provided near one end with a slot F³, and also with a slot F² in the same position relatively to the other end as the slot F² of 70 the tumblers F. The tumblers F⁶ are provided with a slot F⁹ near one end and a slot F¹⁰ in a similar position to the slots F², but having its forward wall rounded, and the tumblers F⁷ are provided with a slot F¹¹ in 75 the upper edge, similar to the slot F¹⁰ of the tumblers F⁶, and have one end rounded at F¹². The sets of tumblers are arranged near the top of the casing C, and the slots formed in their upper edges are adapted to correspond 80 with the transverse slot D, formed in the top of the casing C, so that the cross-piece E' of the locking-bar E can pass into the said slot D and the slots in the tumblers in order to unlock the till A. The two tumblers of each 85 set are operated on by a lever H H' H² H³ H⁴, &c., the upper ends of said levers extending into the slots F⁴ F⁸, formed in the under side of the two tumblers of each set. The levers H, H', H², H³, and H⁴ are all pivoted 90 on a transverse rod H⁵, secured to the sides of the casing C, and the lower ends of these levers pass through a slot A', formed in the bottom of the drawer or till A. To the outer ends of the levers H, H', H², H³, and H⁴ are 95 pivotally connected the rods I, I', I², I³, and I⁴, respectively, extending along the under side of the till A to the front of the same and passing through the bearing A², secured on the under side of the said till. The rods I, I', I², I³, and I⁴ are provided on their outer ends with downwardly-extending finger-pieces J, J', J², J³, and J⁴, respectively, serving for conveniently moving the rods I and the respect-

ive levers II. Each of the latter is provided a short distance above its pivot H⁵ with the two offsets K and K', extending in opposite directions and engaged, respectively, by the 5 free ends of the springs L and L', secured to the casing C. The springs L and L' have the tendency to hold the said levers H in a vertical position, as is plainly shown in Fig. 1.

In the cross-piece E' of the locking-bar E is 10 formed an opening E³, adapted to be engaged by a slightly curved arm N, pivoted at N' to the under side of the table B. When the till A is in its innermost position, the said curved arm N rests on top of the casing C and terminates 15 in front of the cross-bar E' of the locking-bar E. When the locking-bar E is in its lowermost position—that is, in the slot D and the slots in the tops of the tumblers—and the till is drawn outward, the said pivoted 20 arm slides over the top of the casing C without engaging the cross-piece E' of the locking-bar E. When the latter is in its outermost position, as shown in dotted lines in Figs. 5 and 6, then the pivoted arm N passes 25 into the opening E³ of the cross-piece E' of the locking-bar E, when the till A is moved outward, so that the latter can only be moved a short distance and cannot be opened. On the under side of the table B is also secured 30 a projection O, adapted to engage the upper end of a gravity-lever P, hung on the pin E⁴, projecting from the locking-bar E. On the said pin E⁴ is also hung loosely a striker Q, adapted to be engaged by the said gravity-lever P and operating on a bell R, secured to 35 one side of the casing C.

The operation is as follows: When the till A is moved inward, the pivoted arm N rests on top of the casing C and remains at its inner end in front of the cross-piece E' of the locking-bar E, as is plainly shown in Fig. 1. The sets of tumblers are set in such a manner that one, two, or more sets of the said tumblers have their respective upper notches 40 out of line with the cross-slot D when the respective lever H, H', H², H³, or H⁴ is in a vertical position, so that the locking-bar E rests with its cross-piece E' on the top edges of the said respective sets of tumblers, and consequently projects above the top plate of the casing C. Now when a person not knowing the combination pulls the till A outward the arm N passes into the opening E³ on the cross-piece of the locking-bar E, so that the till 45 can only move forward until the cross-piece E' strikes against the lug N² in the arm N. A further outward movement of the till is thus prevented. The lock is set by arranging the tumblers with the letters desired for 50 each key forward combined in sets of two, or one tumbler may be used with each key—that is, to set a key on a put an a and e together on that key; to set on b, put a b and e together; to set on e, put one or two e's on 55 the key; to set on c, the same; to set on d, the same. An a may be put with a c without affecting the c, and a b with a d without af-

flecting the d. In this way tumblers not in the combination may be kept in the lock.

To open the lock, first push the till in as 70 far as it will go and hold it there while manipulating the keys. Now to open the drawer on any combination pull any keys set on a as far forward as they will come and let them go gently back to their normal position. Now 75 push any keys on b and let them back. Now pull any keys set on c and hold them there and push any keys set on d and hold them there and draw the till out. The e is always in position and need not be touched. If the 80 lock is set on e and c only, it works like an ordinary combination-lock. As c and d are the opening-keys, one or more of one or the other must enter every combination. a and b when once put in position need not be 85 touched unless thrown out of position by some one moving the keys or by a sudden jar of the till, as, being notched on the bottom, they are not liable to move. The object of the double tumblers a b is that the lock may 90 be set to open on one key only; but if when so set an unauthorized person attempts to open the till he, by moving the keys not in the combination, displaces these tumblers so that if by accident the right key is moved the till 95 remains locked; but the person knowing the combination can easily replace them by following the directions above set forth, as the long slots f⁴ of these tumblers permit of their 100 being moved to put them in the right position without being displaced by the return movement of the levers II. The bell also rings every time the till is pulled forward.

Having thus described my invention, what I claim as new, and desire to secure by Letters Patent, is—

1. In a combination lock and alarm, the combination, with a casing having a transverse slot in its top and secured in a till, of a locking-bar pivoted on the said casing and adapted to pass into the said slot, and an arm pivoted on the table and adapted to engage an aperture in the said locking-bar, substantially as shown and described.

2. In a combination lock and alarm, the combination, with a casing having a transverse slot and secured in the till, of a locking-bar pivoted on the said casing and adapted to pass into the said slot, an arm pivoted on the table and adapted to engage an aperture in the said locking-bar, and slotted tumblers held to slide longitudinally in the said casing and adapted to be engaged by the said locking-bar, substantially as shown and described.

3. In a combination lock and alarm, the combination, with a casing having a transverse slot and secured in the till, of a locking-bar pivoted on the said casing and adapted to pass into the said slot, an arm pivoted on the table and adapted to engage an aperture in the said locking-bar, slotted tumblers held to slide longitudinally in the said casing and adapted to be engaged by the said locking-bar, levers pivoted in the said casing and serv-

ing to shift the said tumblers, and rods extending along the outside of the till and connected with the said levers, substantially as shown and described.

5 4. In a combination lock and alarm, the combination, with a casing having a transverse slot and secured in a till, of a locking-bar pivoted on the said casing and adapted to pass into the said slot, an arm pivoted on the 10 table and adapted to engage an aperture in the said locking-bar, slotted tumblers held to slide longitudinally in the said casing and adapted to be engaged by the said locking-bar, levers pivoted in the said casing and serving to shift the said tumblers, rods extending along the outside of the till and connected with the said levers, and finger-pieces secured on the front ends of the said rods for operating the latter, substantially as shown and described.

15 5. In a combination lock and alarm, the combination, with a casing having a transverse slot and secured in the till, of a locking-bar pivoted on the said casing and adapted to pass into the said slot, slotted tumblers held 20 to slide longitudinally in the said casing, le-

vers pivoted in the said casing and engaging the said slotted tumblers, rods for operating the said levers and held on the outside of the till, and springs engaging the said levers, so 30 as to hold the latter in an upright position, substantially as shown and described.

6. In a combination lock and alarm, the combination, with a casing having a transverse slot and secured in the till, of slotted 35 tumblers held to slide longitudinally in the said casing, a locking-bar pivoted on the said casing and adapted to pass into the said transverse slot and into the slots of the said tumblers, an arm pivoted to the table and adapted 40 to engage an aperture in the said locking-bar, a fixed projection held on the said table, and a gravity-lever fulcrumed on the said locking-bar, a striker held on the said locking-bar and engaged by the said gravity-lever, and a 45 bell secured to one side of the said casing and operated on by the said striker, substantially as shown and described.
